UNITED STATES PATENT OFFICE.

SAMUEL S. YARRINGTON, OF WILMINGTON, DELAWARE.

CATAMARAN.

996,444.

Specification of Letters Patent. Patented June 27, 1911.

Application filed August 9, 1910. Serial No. 576,378.

To all whom it may concern:

Be it known that I, SAMUEL S. YARRINGTON, a citizen of the United States of America, residing at Wilmington, in the county 5 of Newcastle and State of Delaware, have invented new and useful Improvements in Catamarans, of which the following is a specification.

This invention relates to catamarans, the 10 object of the invention being to provide a new and improved central platform which is yieldingly supported on the parallel shells so that the shells and the platform are relatively movable, thus accommodating for 15 the desired movements of the platform on its sudden contact with the waves.

A still further object of the invention is to construct the said platform of a substantially openwork frame which will permit 20 the water to be forced therethrough on contact of the platform with the waves to prevent such action of the water against the platform from retarding the movement of the vessel.

25 In the drawings, forming a portion of this specification and in which like numerals of reference indicate similar parts in the several views:—Figure 1 is a plan view of my improved catamaran. Fig. 2 is a side 30 view thereof. Fig. 3 is a detail longitudinal section through the platform showing a part of one of the shells in full lines. Fig. 4 is a detail transverse section taken on the line 4—4 of Fig. 1. Fig. 5 is a detail section 35 taken on the line 5—5 of Fig. 1. Fig. 6 is a detail section taken on the line 6—6 of Fig. 1. Fig. 7 is a detail section taken on the line 7—7 of Fig. 6. Fig. 8 is a vertical 40 section through a portion of one of the rudders.

45 My improved catamaran consists of identically formed parallel shells 1 which are formed preferably of hollow metal members constructed to form non-communicating 50 wear chambers or compartments 2, each of such compartments being provided with an inwardly opening check valve 3 through which the desired air pressure may be forced into the shell. From this construction 55 it will be seen that the shells are extremely buoyant and sinking of the vessel is impossible. Near the front end the shells are connected together by the brace 4 which comprises members 5 on the shells, the tie 60 rod 6 which connects the members with each other and the double turn-buckle 7. The

member 8 of the turn-buckle is supported by the standard 9 which extends upwardly from the tie rod 6. The extremities of the member 8 are threaded and they are spaced 60 from the threaded extremities of the members 10 of the turn-buckle so that the adjacent ends are operatively associated to accommodate the adjusting nuts 11. The outer ends of the members 10 are secured 65 to the members 5 as particularly shown in Fig. 4 of the drawings. Each shell is provided on its underside with a suitable keel 12.

Near the rear ends the shells are connected with each other by a brace 13 which is substantially identical in construction with the hereinbefore described brace 4, the difference being in the provision of a depending 70 movably mounted frame 14. The frame 14 is formed to provide a yoke 15 in which the 75 sleeve 16 is mounted. The sleeve 16 is provided with lateral pins 17 which extend through the elongated slots 18 in the yoke.

The shells are provided with front vertical pins 19 and rear vertical pins 20. A 80 platform 21 is provided at the center of the vessel and as illustrated, it consists of a rectangular frame which is formed of the longitudinal side bars 22 and the end bars 23. The bars 23 are connected with each 85 other by parallel spaced slats 24. The bars 22 are connected with each other by the parallel slats 25. This forms a platform of openwork construction for a purpose to be hereinafter described. The end bars 23 are 90 extended beyond the longitudinal side bars and formed in each extended portion is an elongated slot 26. The slotted extremities of the bars 23 fit over the vertical pins 19 and 20 on the shells 1, and as illustrated 95 particularly in Figs. 3 and 4 of the drawings, helical extensible springs or equivalent elastic elements 27 are interposed between the shells and the platform. When springs are employed they are preferably coiled about 100 the vertical pins 19 and 20. A cross member 28 is mounted beneath the platform and its ends are formed to provide trunnions 29 which are mounted in bearings 30 on the shells. A motor 31 is conventionally shown 105 in the drawings. This motor is suitably mounted on the platform 21 at a point immediately in front of the seat 32. The propeller shaft 33 of the motor extends 110 downwardly through the frame and its propeller 34 is located at a point immediately between the shells. The propeller shaft 33

extends through the sleeve 16 so as to revolve freely therein. The clutch rod 35 of the motor is connected with the controlling lever 36 on the platform. This controlling lever preferably extends in an upward direction from the platform at one side of the operator's seat 32. A standard 37 is mounted on the platform at a point in advance of the motor and at the upper end, the standard 37 is constructed for the reception of the battery box 38. By constructing the standard 37 as described the battery box is spaced sufficiently from the platform to prevent its contacting with the water.

15 Each shell is provided at its rear end with superimposed bearings 39 between which the rudder 40 is movably mounted. The rudder is provided with an intermediate squared passage 41 which receives the correspondingly formed shank 42 on the rudder-controlling member. The shank 42 is provided with a depending cylindrical stem 43 which extends through the lower bearing 39. The shank 42 is provided with an upwardly extending cylindrical bearing 44 which extends through the upper bearing 39. Cotter pins or like fastenings 45 extend through the stems 43 and 44 at points outwardly of the bearings. It may be stated that the 30 opening in the bearing 39 is slightly greater than the diameter of the shank 42 and that immediately above the opening and mounted on the stem 44 and at a point below the uppermost cotter pin 45 is a washer 46 whose 35 opening is less than the one formed in the upper bearing 39. When it is desired to remove the rudder the lowermost cotter pin is disengaged from the stem 43 and the shank 42 can be removed by drawing the 40 same upwardly until it is entirely free from the rudder. The uppermost stems 44 of the rudder shanks are provided with crank arms 47. The arms of each shank are operatively connected with the controlling cables 48.

45 These cables are connected with the winding drum 49 which is mounted in a suitable bracket 50 which extends upwardly from the

platform at a point in advance of the operator's seat. A suitable steering wheel 51 is operatively connected with the drum. 50

The construction of the catamaran as described and disclosed herein is extremely simple and will be found most durable in that by providing the yieldingly supported platform the shells will be relieved of considerable strain and the platform will be relieved of considerable wear and tear. By constructing the platform of the herein described cross slats the waves when striking the bottom of the platform will offer little 60 or no resistance in the travel of the vessel as it will be seen that the water can make its escape by way of the passages 52 between the slats of the platform. 65

I claim:

1. A catamaran comprising spaced shells, bearings extending upwardly from each shell midway between the ends thereof, a platform having trunnions mounted in the bearings, the said platform including end members having elongated slots therein, vertical pins extending upwardly from each shell and extending through the slots in the said platform, and springs interposed between the platform and shells respectively and surrounding the said pins. 70

2. A catamaran comprising spaced shells, bars connecting the shells with each other, a platform mounted for rocking movement on the shells and comprising a substantially 80 reticulated structure including front and rear bars having portions extended beyond the sides of the platform and formed to provide elongated slots, pins extending upwardly from each shell, and springs interposed between the said outwardly extended portions of the front and rear bars and between the shells respectively. 85

In testimony whereof I affix my signature in presence of two witnesses.

SAMUEL S. YARRINGTON.
